Giles Thorpe, Letters Patent dated July 10, 1821.

The circumstance referred to in these Letters Patent, & comprising part of the same, containing a description in the words of the said Giles Thorpe, himself, of his improvement on his Spooline Machine Patented on the 10th day of August 1821.

These improvements consist, first, of "carrier wheels" being in number of wheels confined to the say wheels & being wheels on which the carriers ride, and by which they are moved or forced round in their proper seats. They are concave on one side & convex on the other, forming a curve, corresponding with the circle on which they stand. — The rim or edge of these wheels is bevelled coming nearly to an edge of the concave surface of one, and the convex surface of another, so they have a projecting lip, so as to cover half the thickness of each wheel; so that the rims can be butted to each other, thereby allowing a deeper notch for the connecting bars of the carriers to lie in, securing the carriers more safely in their places.

The two plates of the carriers are permanently connected each to the other by two connecting-bars. — Said carriers are so constructed as to receive & hold a spool or bobbin, with the shaft or body of the spool or bobbin being passed with the following the carriers following the shafts to, and in a straight line from the spool or bobbin to the picking roller, where the thread is formed.

The second improvement is in "guiding rim", encompassing the carrier wheels, the use of which is to check the unceasing inclination of the carriers, to prevent them from sliding off the frame and rollers. The surface of this rim is concave corresponding with the curve of the carrier wheels & with the circle on which the carrier wheels are placed. The inner edge of the rim comes so near to the outer edge of the carrier wheel as to admit of no more play to the connecting bars of the carriers while they lie in said notches than that of ..

meaning leading inward to what the space between the vehicles and men. This zone is approached by a road or driveway leading from the rear of the mansion.

The third improvement is a rod attached to the machine for the purpose of rotating the hand, & a pulley the going rollers in bringing it forward. This rod receives its motion from a hand passing over a wheel, belonging & confined to the shaft of the going rollers.

Dealt this 17th day of June 1826. —
